UNITED STATES PATENT OFFICE.

JOHN H. RATHMAN, OF WICHITA, KANSAS.

BATHING SUIT.

Application filed October 19, 1922. Serial No. 595,631.

To all whom it may concern:

Be it known that I, JOHN H. RATHMAN, a citizen of the United States, residing at Wichita, in the county of Sedgwick and 5 State of Kansas, have invented certain new and useful Improvements in Bathing Suits, of which the following is a specification.

The present invention has reference to bathing suits, wherein the same are provided 10 with means formed directly thereon for receiving an air tube or other floatable means whereby the wearer of the suit is prevented from drowning while in bathing, and further serving as a means to assist the bather 15 in practicing the art of swimming.

The primary object of this invention resides in the provision of a bathing suit wherein the same has incorporated therewith either a single pocket member or a plurality 20 of flap members for effectively retaining around the body of the wearer, a pneumatic tube or other floating means for purposes above described.

The nature and advantages of the invention will be better understood when the 25 following detailed description is read in connection with the accompanying drawings, the invention residing in the construction, combination, and arrangement of parts as 30 claimed.

In the drawings forming part of this application, like numerals of reference indicate similar parts in the several views, and wherein:—

35 Figure 1 is a rear elevational view of a bathing suit constructed in accordance with the present invention, a portion of the tube receiving pocket being broken away and shown in cross section.

40 Figure 2 is a fragmentary front elevational view of the suit shown in Figure 1, a portion of the device being also shown in section.

Figure 3 is a rear elevational view of a 45 modified form of the invention.

Figure 4 is a front elevational view of the suit shown in Figure 3, and

50 Figure 5 is a combined cross sectional and perspective view of a form of air tube used by me in accordance with the invention.

Referring to the drawings, and particularly to Figures 1 and 2, there is shown a bathing suit 1 of any desirable form having

stitched or otherwise secured to the waist portion thereof an annularly extending 55 pocket or receptacle 2. This pocket or receptacle 2 is in the form of a relatively large tube and may be constructed of a suitable fabric or the like. Centrally of the rear portion of this tube or receptacle is an 60 enlarged opening 3 provided for the insertion of a pneumatic tube 5.

Having particular reference to Figure 5, this tube is shown as being of a hollow single length of rubber or other material impervious to air and closed at its opposite end portions 6 and 7, the adjacent ends of this tube carrying cloth or leather strap members 8, whereby the ends of the tube are effectively retained together when these 70 said straps are knotted as shown in Figure 1. One of the end portions of the tube 4 has any desirable form of air inlet nipple 9 formed thereon for readily permitting of the filling of the said tube with air. 75

In the modified form of the invention set forth in Figures 3 and 4, the bathing suit 1 is shown as being provided upon the rear side thereof with a pair of suitably spaced flap members 10, these flap members adapted 80 to be stitched or otherwise secured to the suit at the upper end portion thereof as at 11. The lower edge of these flap members have a plurality of spaced button-holes 12 adapted for buttoning over similarly spaced buttons 85 13 secured to the bathing suit. Similarly formed upon the front side of the suit is still another flap member 10, also secured to the bathing suit by a row of stitching 11, and having the usual button connections at its 90 lower edge to the suit.

It will be readily apparent from the description of Figures 3 and 4, that the above described air tube 5 may be conveniently positioned around the waist of the bather to 95 be there retained by the several flap members 10 hereinabove described, and although I have shown and described the means to be retained within the pocket or tube 2 or the flaps 10, as a pneumatic tube, it is nevertheless to be understood that other means may be provided in lieu of this tube for accomplishing similar purposes, such other means being a series of interconnected cork blocks or the like. 100

Other minor changes may be made in the 105

invention without departing from the spirit and scope thereof as claimed.

What I claim as new is:—

In combination with a bathing suit, a plurality of flap members secured at their upper edge portion to the said suit and adapted for supporting an air tube or the

like around the waist of the wearer, for preventing drowning while in bathing, and detachable connections between the opposite ¹⁰ ends of the said flap members and the suit for purposes described.

In testimony whereof I affix my signature.

JOHN H. RATHMAN.
